Fig. 2

Fig. 1 is a view in perspective of a child's chair showing my new design with the tray in horizontal position; and Fig. 2 is a similar view of the chair showing the tray in elevated position.

The salient feature of my new design consists in the figure of a seated animal with its hind legs extended in spaced parallel relation providing the arms of a chair and its fore legs supporting a tray resting on the upturned toes of the hind legs.
